[57] CLAIM

The ornamental design for handset telephone, as shown
and described.

DESCRIPTION

FIG. 1 is a top and right side perspective view of a
handset telephone showing my new design;

FIG. 2 is a top plan view thereof;

FIG. 3 is a left side elevational view;

FIG. 4 is a bottom plan view thereof;

FIG. 5 is a back end elevational view thereof; and
FIG. 6 is a front, cord-end, elevational view thereof.

The showing of a cord in fragmentary form is for ease
of illustration.
